UNITED STATES PATENT OFFICE

SAMUEL RUBEN, OF NEW YORK, N. Y., ASSIGNOR TO RUBEN TUBE COMPANY, A CORPORATION OF DELAWARE

VACUUM TUBE AND ITS ELEMENTS

Application filed August 26, 1927. Serial No. 215,753.

This invention relates to a vacuum tube and more particularly to a vacuum tube utilizing alternating current for heating the cathode and to the elements thereof.

6 The chief object of the invention is to provide a vacuum tube operating upon an alternating current circuit having high thermal efficiency with a minimum thermal lag.

In addition to having a high thermionic 10 efficiency, a vacuum tube must be prompt in its response to the application of the alternating current; that is, the thermal lag must be a minimum in that the time elapsing between the application of the cathode heating 15 or alternating current and the time when there is sufficient electron emission from the cathode element must be brief to be practicable. The tube of my present invention employs a heating element contacting with an 20 electrically conductive element of higher specific resistance, which is in surface contact with a cathode element having a surface capable of copious electron emission.

In a preferred form of construction of the 25 tube of my present invention, a graphite member or rod is used as the electrically conductive element of relatively high specific resistance; upon this the heater wire or element in the alternating current circuit is 30 wound; also upon the conductive member, but not contacting with the heater wire, in surface contact therewith, is the cathode element which has a surface of high electron emissivity.

35 The graphite rod is spirally threaded so that a shallow groove is spirally cut along its cylindrical surface in which the heater wire fits just below the surface of the rod. A thin nickel tube, with its outer surface coated with an oxide of an alkaline earth, such as barium or strontium, or a mixture of both, is placed in surface contact with the carbon rod.

40 Due to the good thermal conductivity of the graphite or carbon rod and the shunt path between the heater element and the nickel cylinder, the cathode is rapidly raised to thermionic emission temperature.

45 As the conductive graphite rod separates the heater wire from the nickel cathode cyl-

inder, there is a leakage current through the rod from opposite ends of the heating filament which assists in heating the cathode and tends to stabilize the temperature and reduce thermal fluctuations due to line variations, and to reduce the alternating current noise or 55 hum by reducing the intensity of the electrical field produced by the heating current.

It is desirable, of course, to employ in any 60 electron emission tube a cathode having a high degree of emissivity at relatively low temperatures. I have obtained the best results by applying to a suitable cathode metal base, in this case the nickel cylinder, an alkaline earth coating composed of equal parts 65 by weight of barium and strontium oxides finely ground and thoroughly mixed with one tenth of the total weight of powdered resin; to the three constituents is added a resin solvent until the whole forms a suitable paste. 70 Before applying the paste the nickel surface is preferably oxidized, the oxide on being heated in contact with the mixture being chemically reduced by the resin so that there 75 is effected a very intimate contact between the alkaline earth oxides and the nickel surface. When the mixture has been applied in any suitable manner to the oxidized nickel surface and has been air dried, the whole is baked to 80 about 200° centigrade, after which the resin 85 is burned out.

85 My experiments have shown that a high electron emission is obtained from such a cathode at a temperature materially lower than by cathodes coated with alkaline earth compounds by the methods known to the art; and further, I have found that any substantial deviation from the above formula for the mixture yields a materially lower efficiency.

90 The intimate surface contact of a very thin coating of the alkaline earth oxides with the nickel minimizes the thermal and electrical resistance of the element, and therefore, the requisite cathode metal temperature.

95 A cathode made in accordance with the method described is efficient not only in the higher vacuum tubes, such as those employed in radio signal transmission and reception, but in what are termed low pressure devices,

such as those employing ionization discharges through gases for illumination, etc.

For a better understanding of the invention reference is made to an embodiment 5 thereof in the accompanying drawings, in which:

Fig. 1 represents a vacuum tube with its cathode heater and other elements contained; Fig. 2 the conductive rod of graphite, which 10 is one-sixteenth of an inch in diameter and has a resistance of 100 ohms per longitudinal inch and is superficially threaded (five threads to the inch) to a depth of about .006 inch. Fig. 3 represents a section plan view 15 of the tube and its elements.

At 1 is a nickel cathode element coated with a mixture containing strontium and barium oxides, 2 the anode cylinder having therewithin the wire grid 3. The cathode is 20 supported by conductive rods 1a and 1b; the anode 2 is supported by rods 2a and 2b and the grid 3 by rod 3a. The rods 1a, 2a and 3a are adapted for connection in an electric circuit. Spirally wound on the surface of a 25 graphite rod 5 is the heater wire, lying within in a groove below the surface. The spirally wound heater wire of tungsten is supported and adapted for connection in the heater circuit by rods 4a and 4b. The cathode cylinder 1 fits closely upon the graphite rod 5, but not in contact with the heater wire 4 wound 30 in the groove on the surface of carbon rod 5. The oxide coating on the nickel cylinder 1 is previously coated with the mixture made 35 of powdered barium and strontium oxides with resin and a resin solvent to effect the copious emission of electrons, which occurs at relatively low temperatures to the anode 2, the electron stream being controlled by the 40 grid element 3 between the cathode and anode. While the graphite or carbon is considered preferable for the heater element base and as a separator between the heater wire and the cathode, other electrically 45 conductive materials having resistances higher than the heater elements, to limit leakage currents, can be used, such as metallic alloys of chromium and metallic compounds of carbon.

50 What I claim is:

1. A sealed evacuated envelope containing, a cathode, an anode, a grid and a heater element for indirectly heating the cathode to emission temperature, comprising a conductive filament mounted in a groove adjacent the periphery of a conducting member having a specific resistance higher than that of said conductive filament.
- 55 2. A sealed evacuated envelope containing, a grid, an anode, an indirectly heated cathode having a coating of alkaline earth oxides and a heater element for heating the cathode to emission temperature, comprising a conductive filament mounted upon a conductive

member having a specific resistance higher than that of said conductive filament.

3. A sealed evacuated envelope containing, a cathode, an anode, a grid and means for heating the cathode to emission temperature, comprising a conductive element mounted upon a graphite rod. 70

4. A sealed evacuated envelope containing, a grid, an anode, a cathode having a coating of alkaline earth oxides and means for heating the cathode to emission temperature, comprising a conductive element mounted upon a graphite rod, said cathode also being mounted upon and in surface contact with said graphite rod. 75

5. A sealed evacuated envelope containing, a cathode, an anode, a grid and a heater element for indirectly heating the cathode to emission temperature, comprising a conductive filament mounted upon a conductive member having a specific resistance higher than that of said conductive element, the cathode also being mounted upon and in surface contact with said conductive member. 80

6. A sealed evacuated envelope containing, a cathode, an anode, a grid and a heater element for indirectly heating the cathode to emission temperature, said heater element comprising a conductive filament mounted on a graphite member in a helical groove adjacent the periphery of said member. 90

7. A sealed evacuated envelope containing, a cathode, an anode, a grid and a heater element for indirectly heating the cathode to emission temperature, said heater element comprising a conductive filament mounted in a helical groove adjacent the periphery of a graphite member, the cathode being in surface contact with said member, but not in contact with said heater element. 100

8. A sealed evacuated envelope containing an indirectly heated cathode having a coating of barium and strontium oxides, an anode, a grid and a heater element for heating the cathode to emission temperature, said heater element comprising a conductive element, mounted on a graphite member in a helical groove adjacent the periphery of said member. 110

In testimony whereof, SAMUEL RUBEN has signed his name to this specification this 25th day of August, 1927.

SAMUEL RUBEN.
